COMPOSITE NOZZLE

BACKGROUND OF THE INVENTION

In radial inward flow turbine nozzles, erosion of the inner surface of the nozzle by dirt and/or liquid particles thrown outward by the turbine wheel blades can greatly reduce the life of the nozzle. Attempts to provide a nozzle of erosion resistant material have proven to be uneconomical in view of the close dimensional tolerances required in order to control the turbine flow rate through the nozzle passages.

SUMMARY OF THE INVENTION

The present invention provides a composite nozzle having an outer nozzle ring of an easily machinable material to provide close dimensional tolerances for the nozzle passage therethrough and an inner nozzle ring of erosion resistant material with slightly larger nozzle passages therethrough and having relaxed tolerances.

BRIEF DESCRIPTION OF THE DRAWINGS

FIG. 1 is a partial sectional view of a radial inward flow turbine illustrating the composite nozzle of the present invention.

FIG. 2 is a sectional view of the composite nozzle portion of the radial inward flow turbine of FIG. 1 taken along line 2-2.

FIG. 3 is a sectional view of the composite nozzle of FIG. 2 taken along line 3-3.

DESCRIPTION OF THE PREFERRED EMBODIMENTS

As illustrated in FIG. 1, the radial inward flow turbine generally comprises a torus assembly 10 mounted between supports 12, 14 positioned on a turbine nozzle 16. Packings 18 and 20 may be provided between the nozzle 16 and the supports 12 and 14 respectively. The nozzle 16 having an outer nozzle ring 17 may be constructed of any easily machinable material, such as steel, which can be fabricated to close dimensional tolerances. A turbine wheel 21 including blades 22 is adapted to rotate between the nozzle 16 and a seal 24.

The inner nozzle ring 26, of an erosion resistant material such as cemented carbide, or other sintered material such as aluminum oxide, is provided between the radial outward end of the turbine blades 22 and the outer nozzle ring 17. The inner nozzle ring 26 may be held in position by a groove 28 in the nozzle 16 and/or by a plurality of screws 30 (and washers 32) threaded into the outer nozzle ring 17. An elastomeric seal, such as silicone rubber cement, may be provided between mating surfaces of the outer nozzle ring 17 and inner nozzle ring 26. The seal 24 extends upward between the nozzle 16 and the turbine housing assembly 34. Shims 36 and 38 can be provided between this upward extending seal 24 and the housing assembly 34 and inner nozzle ring 26, respectively.

As shown more clearly in FIGS. 2 and 3, at least one row of spaced nozzle passages 40 extend around the outer nozzle ring 17. Two rows of individually staggered passages 40 are illustrated. These passages 40 may be provided with an enlarged tapered inlet section 42 to facilitate flow entry. Aligned with the individual passages 40 in outer nozzle ring 17 are a plurality of individual passages 44 in the inner nozzle ring 26. With the nozzle 16 including outer nozzle ring 17 constructed of an easily fabricated material such as steel,

the nozzle passages 40 can be machined to a precise dimension holding close tolerances, sufficient to control the turbine flow rate as required. The inner nozzle ring 26, being constructed of an erosion resistant material, is not susceptible to being machined to close tolerances and, accordingly, the flow area of individual nozzle passages 44 should be slightly greater than the flow area of individual nozzle passages 40.

For example, if the diameter of nozzle passages 40 is 10 designated as D_1 having a tolerance of T_1 , the diameter D_2 of nozzle passages 44 would be slightly greater than D_1 and have a tolerance T_2 considerably greater than tolerance T_1 , with the limitation that $(D_2 - T_2)$ is still greater than or equal to $(D_1 + T_1)$.

15 In this way the erosion resistant material is provided in the area where it is required, thus greatly enhancing the nozzle life. In addition, erosion damage to the turbine wheel is also reduced. The composite nozzle can be economically produced, since relatively large dimensional tolerances can be accommodated by the erosion resistant material. The nozzle throat which controls the turbine flow rate is incorporated into the outer nozzle ring which can be fabricated to close dimensional tolerances.

20 While specific embodiments of the invention have been illustrated and described, it is to be understood that these embodiments are provided by way of example only and that the invention is not to be construed as being limited thereto, but only by the proper scope 30 of the following claims.

What I claim is:

1. A composite nozzle for a radial inward flow turbine wheel comprising:

an outer nozzle ring having a plurality of spaced nozzle passages extending therethrough; and
35 an inner nozzle ring of an erosion resistant material disposed radially inward from the outer nozzle ring and having a plurality of spaced nozzle passages extending therethrough individually aligned with the spaced nozzle passages of said outer nozzle ring to receive a flow of fluid therefrom, said inner nozzle ring radially disposed around said turbine wheel to deliver a flow of fluid thereto.

40 2. The composite nozzle of claim 1 wherein the spaced nozzle passages of said inner nozzle ring have a greater cross-sectional flow area than the spaced nozzle passages of said outer nozzle ring.

45 3. A composite nozzle for a radial inward flow turbine wheel comprising:

an outer nozzle ring having a plurality of spaced nozzle passages extending therethrough, said outer nozzle ring spaced nozzle passages having a cross-sectional flow dimension D_1 with a dimensional tolerance T_1 ; and
50

55 an inner nozzle ring of an erosion resistant material disposed radially inward from the outer nozzle ring and having a plurality of spaced nozzle passages extending therethrough individually aligned with the spaced nozzle passages of said outer nozzle ring, said inner nozzle ring spaced nozzle passages receiving a flow of fluid from said spaced nozzle passages of said outer nozzle ring and having a cross-sectional flow dimension D_2 greater than D_1 and with a dimensional tolerance T_2 greater than T_1 such that $D_2 - T_2$ is at least equal to $D_1 + T_1$, said inner nozzle ring radially disposed around said turbine wheel to deliver a flow of fluid thereto.

4. The composite nozzle of claim 3 wherein $D_2 - T_2$ is greater than $D_1 + T_1$.
5. The composite nozzle of claim 3 and in addition elastomeric seal means disposed between said outer nozzle ring and said inner nozzle ring.
6. The composite nozzle of claim 3 wherein the spaced nozzle passages of said outer nozzle ring have an enlarged tapered inlet section.
7. The composite nozzle of claim 3 wherein said plurality of spaced nozzle passages comprise two circumferential rows of staggered nozzle passages.
8. The composite nozzle of claim 3 wherein said inner nozzle ring is a sintered material.
9. The composite nozzle of claim 5 wherein said elastomeric seal means is a silicone rubber cement.
10. The composite nozzle of claim 1 wherein the spaced nozzle passages extending through said inner nozzle ring are substantially the same cross-sectional configuration as the spaced nozzle passages extending through said outer nozzle ring.
11. The composite nozzle of claim 3 wherein the spaced nozzle passages extending through said inner nozzle ring are substantially the same cross-sectional configuration as the spaced nozzle passages extending through said outer nozzle ring.
12. In combination:
- a radial turbine wheel; and

5

a turbine housing to rotatably support said turbine wheel therein and direct the flow of fluid thereto, said turbine housing including a composite nozzle radially disposed around said turbine wheel to direct the flow of fluid from said housing to said radial turbine wheel;

10

said composite nozzle comprising an outer nozzle ring having a plurality of spaced nozzle passages extending therethrough and an inner nozzle ring of an erosion resistant material disposed radially inward from said outer nozzle ring and having a plurality of spaced nozzle passages extending therethrough individually aligned with the spaced nozzle passages of said outer nozzle ring, the flow of fluid from said turbine housing to said radial turbine wheel being first through the spaced nozzle passages of said outer nozzle ring and then through the spaced nozzle passages of said inner nozzle ring.

15

13. The combination of claim 12 wherein the spaced nozzle passages of said inner nozzle ring are substantially the same cross-sectional configuration as the spaced nozzle passages of said outer nozzle ring.

20

14. The composite nozzle of claim 13 wherein the spaced nozzle passages of said inner nozzle ring have a greater cross-sectional flow area than the spaced nozzle passages of said outer nozzle ring.
